METHOD OF RETURNING GAS TO GAS-
PRODUCING FORMATIONSDaniel E. Conlon, Jr., Upper Darby, Pa., assignor
to The Atlantic Refining Company, Philadelphia, Pa., a corporation of Pennsylvania

Application December 13, 1939, Serial No. 309,035

7 Claims. (Cl. 166—21)

The present invention relates to a method of returning gas to gas and/or oil-producing formations, and more particularly to formations producing at relatively high pressures.

A principal object of this invention is a method of returning to a high pressure gas-producing formation, "lean" gas or gas which has been stripped of its content of liquid or liquefiable hydrocarbons, in order to conserve the gas as well as the pressure naturally existing in the producing formation.

A further object of this invention is a method of returning gas to a gas-producing formation associated with a crude oil-producing formation, in order to repressurize the formation or to maintain a pressure in the formation sufficient to deliver crude oil to the earth's surface without resort to expensive pumping operations.

A further object of this invention is a method of returning gas to a high pressure gas-producing formation in such a manner that pressures substantially lower than the normal well head pressure may be employed in introducing the gas into the input well.

In the operation of high pressure wells of the gas distillate type, wherein the gas produced by the well is subjected to treatment for the separation therefrom of liquid or liquefiable hydrocarbons, it has been found desirable and in many cases mandatory, that the gas denuded of liquefiable hydrocarbons be returned to the gas-producing formation, in order to minimize depletion of the natural pressure in the formation. In the treatment for separating liquefiable hydrocarbons from the well gas, loss of pressure is, to a great extent, unavoidable. And in order to return the denuded gas to the producing formation, it is therefore necessary to recompress the gas to a pressure slightly above that existing at the well head, introduce the recompressed gas into the well, and conduct the gas downwardly through the well to the producing formation, against the gas pressure existing in said formation. For example, gas containing liquefiable hydrocarbons of the nature of gasoline may be withdrawn from a gas distillate well producing at a well head pressure of the order of 3500 lbs./sq. in. This gas may be stripped of its liquefiable hydrocarbon content, for example, by absorption at elevated pressure, and the stripped gas may be delivered to the return compressor at a pressure of about 3200-3300 lbs./sq. in. In order to return this gas to the producing formation through an adjacent input well, such gas is recompressed to a pressure at least as great as the

well head pressure, and preferably somewhat in excess thereof, for example, 3600 lbs./sq. in., and is introduced into the input well against the pressure existing at the well head. By operating in this manner, it is necessary to employ compressors capable of continuously delivering the desired volume of stripped gas to the input well at relatively high pressure, i. e., of the order of 3600 lbs./sq. in. Compressors or pumps suitable for high pressure operation are expensive both with respect to installation as well as maintenance.

However, in accordance with my invention, I am able to return gas to a high pressure formation without recourse to compressors or pumps capable of continuously delivering gas to the input well at pressures greater than normal well head pressure. In other words, I am able to return gas to the gas-producing formation at pump pressures substantially lower than those normally existing at the head of the input well.

Briefly, my invention comprises introducing gas and liquid, such as water, oil, or drilling mud, or the equivalent, into the input well, and conducting the gas and liquid downwardly through the well in such a manner that the liquid exerts a hydrostatic pressure upon the gas sufficient to overcome, at least in part, the gas pressure existing at the bottom of the well, i. e., the formation pressure. The gas is separated from the liquid adjacent the bottom of the well, and the liquid is forced to the earth's surface by the pressure existing in the well, the gas passing from the well into the formation. If desired, both the gas and the liquid may be passed from the well into the producing formation. By operating in this manner, a considerable portion of the formation pressure is overcome by the hydrostatic head of the liquid introduced with the gas, thus permitting the use of lower pump pressures than would be required if no liquid was employed.

My invention may be illustrated with reference to the accompanying drawing, in which Figures 1 and 2 represent diagrammatically apparatus which may be employed in carrying out my invention.

Referring to Fig. 1, (A) represents a gas-producing well comprising a casing 1 provided with perforations 2 communicating with the gas-producing formation surrounding the bottom of the well. Within the casing 1 is disposed a tubing string 3 for conducting to the earth's surface, high pressure gas containing liquefiable hydrocarbons. The well (A) may have a depth of 8000 feet, the gas pressure at the bottom of the

well being, for example, 4300 lbs./sq. in., and at the well head, 3500 lbs./sq. in. The gas containing liquefiable hydrocarbons is withdrawn from the well head at a pressure of 3500 lbs./sq. in. and is passed by means of valve-controlled pipe 4 to a suitable liquid hydrocarbon recovery apparatus 5, which may be an absorption tower operating at a pressure of, for example, 2500 lbs./sq. in. Other conventional apparatus for recovery of liquefiable hydrocarbons may be employed, such as a low pressure separator, or a low pressure absorber, or a retrograde condensation system such as is shown in U. S. Patent #2,133,744 to Vaughan. Since the liquefiable hydrocarbon recovery apparatus is exemplary only and forms no part of my invention, further detailed discussion thereof is unnecessary. Suffice to say that recovered liquefiable hydrocarbons, for example, of the nature of gasoline, are withdrawn from the apparatus 5 through valve-controlled pipe 6 and disposed of as desired. Gas stripped of liquefiable hydrocarbons is withdrawn from the apparatus 5 at a pressure of, for example, 2500 lbs./sq. in., and is returned to the gas-producing formation via input well (B) as hereinafter described.

Input well (B) comprises a casing 1 provided with perforations 8 communicating with the gas-producing formation surrounding the bottom of said casing. Within the casing 1 is disposed a tubing string 9 terminating above the perforated lower section of casing 1. The annular space between casing 1 and tubing 9 is blocked off adjacent the lower end of tubing 9 by means of a packer 10 provided with a pipe 11 terminating adjacent the bottom of the well.

Assuming the gas pressures in the top and bottom of input well (B) to be substantially the same as that existing in the top and bottom of the producing well (A), i. e., 3500 lbs./sq. in., and 4300 lbs./sq. in. at 8000 feet, respectively, it would be necessary, under normal conditions, to introduce stripped gas into well (B) at a pressure somewhat in excess of the well head pressure, for example, 3600 lbs./sq. in., in order to return gas to the producing formation. The difference in pressure between the top and bottom of the well is substantially accounted for by the weight of the column of gas within the well, which may exert a pressure of the order of 800 lbs./sq. in. in an 8,000 foot well.

In order to return stripped gas to input well (B) at lower pump pressures than would ordinarily be required, I first introduce a liquid, for example, water, into tubing string 9 in such quantity as to fill the tubing 9, the bottom of the casing to a level indicated at 12, the pipe 11, and the casing 1 above the packer 10, the gas pressure at the bottom of the well being sufficient to force the water in the casing upwardly to the well head at the earth's surface. The initial charge of water may be introduced from a source (not shown) through valve-controlled pipe 13 to a low capacity auxiliary pump 14, whence it is delivered through pipe 15, injector 16, and pipe 17 into tubing string 9 at a pressure sufficient to overcome the gas pressure at the well head, i. e., 3500 lbs./sq. in. The water is forced down the tubing string 9 and discharges into the bottom of the casing 1. When sufficient water has collected in the bottom of the casing to submerge the lower end of pipe 11, the gas pressure existing at the bottom of the casing forces the water upwardly through tubing section 11 and casing 1 above the packer 10, thus displacing the

gas contained in the casing above the packer 10. This gas may be vented from the top of casing 1 through valve-controlled pipe 18, gas separator 19 and valve-controlled pipe 20, valves 21 and 22 being closed. When the casing 1 has been filled with water, and water appears in the separator 19, the supply of water from an extraneous source is shut off by closing valve 13, and stripped gas, at a pressure of, for example, 2500 lbs./sq. in., is passed from hydrocarbon recovery apparatus 5 through valve-controlled pipe 23 to injector 16, valves 20 and 22 being closed and valve 21 being opened. The high pressure gas passing through injector 16 is introduced through pipe 17 into the upper end of tubing string 9, thus forcing the water in the tubing string downwardly into the bottom of the well, whence it is passed by pipe 11 to casing 1, and thence upwardly through the casing to the casing head. The water is withdrawn from the casing head through valve-controlled pipe 18 and passed to gas separator 19, and is discharged therefrom by means of valve-controlled pipe 21.

When the desired volume of water has been displaced from the tubing string 9, and removed from the system, for example, one-half of the volume initially contained in the tubing string, valve 21 is closed and valve 22 is opened, and water is continuously withdrawn from the top of casing 1 and passed to separator 19, wherein entrained or dissolved gas is separated from the water and may be vented by valve-controlled pipe 20, when necessary. Water, substantially freed of gas, is withdrawn from separator 19 and is passed, by means of valve-controlled pipe 22, to auxiliary pump 14 and is pumped therefrom, at suitably elevated pressure, for example, 2500 lbs./sq. in., through pipe 15 to injector 16, wherein it is mixed with high pressure stripped gas from apparatus 5. The mixture of high pressure stripped gas and water is then continuously fed by the injector 16 through pipe 17 into the top of tubing string 9, and is conducted downwardly through the tubing string in such a manner that the water exerts a hydrostatic pressure upon the gas in the tubing sufficient to overcome, at least in part, the gas pressure existing at the bottom of the well. By proper regulation of the quantities of gas and water and the rate at which they are charged to the injector, the mixture of gas and water discharged from the injector may take the form of a foam, or by periodically interrupting the flow of gas or water to the injector by means of valves 23 and 22 respectively, a series 55 of alternate slugs of gas and of water may be produced. In either case, the object is to introduce and conduct the gas and water down the tubing string 9 in such state that the water will exert a hydrostatic pressure upon the gas as it flows through the tubing to the bottom of the well. The gas and water are discharged from the lower end of tubing string 9 into the casing 1 below the packer 10, the water separating from the gas by difference in gravity. The gas is 60 passed from the casing by means of perforations 8 into the gas-producing formation surrounding the lower section of the well, and the separated water collecting in the bottom of casing 1 is continuously forced, by the well bottom gas pressure, upwardly through pipe 11 into casing 1 above packer 10, and thence upwardly through the casing to the casing head, from which it is withdrawn at elevated pressure for recirculation to the injector 16. In the event that the stripped gas from apparatus 5 is at a pressure too low

for satisfactory operation of injector 16, such gas may be passed from the apparatus 5 through valve-controlled pipe 24 to compressor 25, and thence delivered at higher pressure through pipes 26 and 23 to injector 16.

Assuming that the system is in continuous operation and has reached an operating equilibrium in which the gas and the water each occupy half of the total volume of tubing string 9, it will be apparent that in the 8,000 foot tubing string, the weight of the water will exert a pressure of about 1735 lbs./sq. in. and the weight of the gas will exert a pressure of about 345 lbs./sq. in., against a gas pressure of 4300 lbs./sq. in. at the bottom of the well. Therefore, the pressure required to continuously introduce gas and water, either as a mixture, foam, or in slugs, into the top of the tubing string will be of the order of 2220 lbs./sq. in. as against 3500 to 3600 lbs./sq. in. required if no water was employed in partially counter-balancing or overcoming the 4300 lbs./sq. in. well bottom pressure. And the water passing upwardly through casing 7 for recirculation to the injector 16, will exert a pressure of the order of 3470 lbs./sq. in. at the packer 10, which is approximately 8000 feet below the earth's surface. Therefore the water issuing from the top of casing 7 for recirculation will be under a pressure of about 830 lbs./sq. in.

From the description of my method above given, it will be apparent that once the gas return system is in operation, and the stripped gas is delivered to the return system at a sufficiently high pressure, the gas may be introduced into the well at substantially lower pressures than would be necessary if no liquid was employed to partially overcome the gas pressure existing in the well. While it is usually desirable to withdraw the liquid from the well, it is to be understood that such liquid may be passed from the casing, together with the gas, into the producing formation surrounding the well.

In Figure 2 of the drawing is shown a modification of the input well (B) of Figure 1, wherein the gas and liquid are introduced into the top of casing 7' by means of valve-controlled pipe 17' and flow downwardly through the casing in such a manner that the liquid exerts a hydrostatic pressure upon the gas. The gas and liquid pass through the short pipe 11' provided in packer 10', and are separated adjacent the bottom of the well, the gas flowing through the perforations 8' into the gas-producing formation surrounding the bottom of the well, and the liquid collecting at 12' being forced upwardly to the earth's surface through tubing string 9' by the gas pressure existing at the bottom of the well. Liquid withdrawn from the upper end of tubing string 9' may be passed by means of pipe 18' to a gas separator and thence to a pump and an injector such as is shown in Figure 1, for recirculation to the well casing, along with gas to be returned to the well.

While my method of returning gas to a gas-producing formation is designed primarily for use in conjunction with gas distillate wells, it is also applicable to the return of gas to oil-producing formations to repressurize same or to maintain the gas pressure naturally existing in the oil-producing formation.

What I claim is:

1. The method of returning gas to a high pressure gas-producing formation, which comprises introducing gas and liquid into a well communicating with said formation, conducting said gas

and liquid downwardly through said well in such a manner that the liquid exerts a hydrostatic pressure upon the gas sufficient to overcome, at least in part, the gas pressure existing in said well, separating said gas from said liquid adjacent the bottom of said well, passing said separated liquid upwardly and out of said well, and flowing said separated gas into the gas-producing formation surrounding said well.

2. The method of returning gas to a high pressure gas-producing formation, which comprises introducing a mixture of gas and liquid into a well communicating with said formation, conducting said mixture downwardly through said well in such a manner that the liquid component of said mixture exerts a hydrostatic pressure upon the gas component thereof sufficient to overcome, at least in part, the gas pressure existing in said well, separating said mixture into gas and liquid components adjacent the bottom of said well, passing said separated liquid component upwardly and out of said well, and flowing said separated gas into the gas-producing formation surrounding said well.

3. The method of returning gas to a high pressure gas-producing formation, which comprises alternately introducing gas and liquid into a well communicating with said formation, conducting said gas and liquid downwardly through said well in a succession of gas and liquid slugs, said liquid slugs exerting a hydrostatic pressure upon the gas sufficient to overcome, at least in part, the gas pressure existing in said well, separating said gas from said liquid adjacent the bottom of said well, passing said separated liquid upwardly and out of said well, and flowing said separated gas into the gas-producing formation surrounding said well.

4. The method of returning gas to a high pressure gas-producing formation through a well having a casing and a tubing string terminating adjacent the bottom of said well, which comprises introducing a mixture of gas and liquid into said tubing string, causing said mixture to flow downwardly through said tubing and to discharge therefrom into said casing adjacent the bottom thereof, separating said liquid from the mixture so discharged, withdrawing said separated liquid from said casing, and flowing said gas from said casing into the gas-producing formation surrounding said well.

5. The method of returning gas to a high pressure gas-producing formation through a well having a casing and a tubing string terminating adjacent the bottom of said well, which comprises introducing a mixture of gas and liquid into said tubing string, causing said mixture to flow downwardly through said tubing in such a manner that the liquid component of said mixture exerts a hydrostatic pressure upon the gas component thereof sufficient to overcome, at least in part, the gas pressure existing in said well, discharging said mixture from said tubing into said casing adjacent the bottom of said well, separating said liquid from the mixture so discharged, withdrawing said separated liquid from said casing, and flowing said gas from said casing into the gas-producing formation surrounding said well.

6. The method recited in claim 5, wherein the liquid employed is water.

7. The method of returning gas to a high pressure gas-producing formation, which comprises introducing adjacent the top of a well communicating with said formation, gas and liquid at a pressure substantially lower than that existing

adjacent the bottom of the well, causing the liquid to exert a hydrostatic pressure upon the gas, which, in conjunction with the introductory pressure, is sufficient to overcome the gas pressure existing adjacent the bottom of said well thereby forcing said gas downwardly through said well, separating said gas from said liquid

adjacent the bottom of said well, forcing said separated liquid upwardly and out of said well by means of the gas pressure existing at the bottom of said well, and flowing said separated gas into the gas-producing formation surrounding said well.
